[57] CLAIM

The ornamental design for a truck body side panel, as shown and described.

DESCRIPTION

FIG. 1 is a perspective view of a first embodiment of a truck body side panel showing our new design;

FIG. 2 is a side elevational view of the outer surface thereof; FIG. 3 is a side elevational view of the interior surface thereof;

FIG. 4 is a front elevational view thereof;

FIG. 5 is a rear elevational view thereof;

FIG. 6 is a top plan view thereof; and

FIG. 7 is a bottom plan view thereof;

FIG. 8 is a side elevational view of the outer surface of a second embodiment of our new design;

FIG. 9 is a side elevational view of the interior surface thereof;

FIG. 10 is a front elevational view thereof;

FIG. 11 is a rear elevational view thereof;

FIG. 12 is a top plan view thereof; and

FIG. 13 is a bottom plan view thereof;

FIG. 14 is a side elevational view of the outer surface of a third embodiment of our new design;

FIG. 15 is a side elevational view of the interior surface thereof;

FIG. 16 is a front elevational view thereof;

FIG. 17 is a rear elevational view thereof;

FIG. 18 is a top plan view thereof; and,

FIG. 19 is a bottom plan view thereof.

The broken line showings are for illustrative purposes only and form no part of the claimed design.
